UNITED STATES PATENT OFFICE.

JACOB BARAM, OF WOONSOCKET, RHODE ISLAND.

AUTO SAFETY DEVICE.

Application filed July 1, 1924. Serial No. 723,597.

To all whom it may concern:

Be it known that I, JACOB BARAM, a citizen of the United States, residing at Woonsocket, in the county of Providence and State of Rhode Island, have invented new and useful Improvements in Auto Safety Devices, of which the following is a specification.

My present invention pertains to fenders, and it contemplates the provision on a motor vehicle or the like, of means whereby injury to a pedestrian who is struck by the fender will be precluded and the liability of said person falling beneath the front wheels of the vehicle is materially overcome.

The invention also contemplates the provision in a fender of means whereby the action of a body contacting with the fender will cause a guard to fall and hence the body of the person is received on the fender.

The invention in all of its details will be fully understood from the following description and claims when the same are read in connection with the drawings forming part of this specification in which:

Figure 1 is a perspective view of a portion of a motor vehicle equipped with my novel invention.

Figure 2 is a detail view of the arrangement of curtain and roller and the pawl and ratchet for preventing the roller from rotating under normal conditions.

Figure 3 is a side elevation of the arrangement of pawl and ratchet with respect to a portion of one of the brace frames.

My novel device comprises the arms 1 that may be provided with the cross bars 2 as illustrated and there may be two or more of these cross-bars in the discretion of those using the device.

Secured at either side of the front portion of a motor vehicle and preferably at the lower ends of the hood cover are arms 3 that extend forwardly and are secured to the portions 1 of the fender by the members 14. These members 14 are so constructed that pressure on the lower brace-rod 2 will cause the upper portion of the arms 1 to move forwardly. This is a very important feature of my invention as will appear from the future description of the device.

As shown in Figure 1 I provide a spring 4 that is secured to one of the arms 1 and to one of the portions 3 and hence when the upper end of the arms 1 move forwardly

the spring will tend to return said arms 1 to their proper positions.

At the upper ends of the rods 1 I provide a roller 8 that receives the curtain or canvas 5 and the said roller 8 is provided with the interior spring 9 and operates after the fashion of the well known window shade.

On its free edge the curtain or canvas is provided with a strip of metal or other suitable material and secured to the strip on each side of the curtain is a cord 6 that passes over pulleys or rollers that rotate on the lower rod 2 and the said cords are then fixedly secured on the roller 8 at each side of the curtain.

On one end of the roller 8 and outside of the left-hand member 1, I provide the ratchet 10 and secured on the before mentioned member 1 and adapted to engage said ratchet 10 is a pawl 11. This pawl is secured to the arm 1 by the bolt 12 and at its end below the ratchet the pawl is provided with the arm 13 that rests in a slot in the left-hand arm 3. On the end of the roller 8 outside the ratchet 10 I provide a square end portion 15 through the medium of which a key or other means may be employed to place the spring 9 under tension.

In the practical use of my invention the spring 9 is placed under tension and the curtain or canvas assumes the position shown in Figure 1.

Should a person be struck by the lower end of the fender, which naturally is the first portion of the fender that could possibly strike a person, the pressure exerted on the lower end of the fender will naturally rock the upper end of the members 1 forwardly. This forward rocking will release the lower end 13 of the pawl from the arms 3 and the upper end of the pawl will naturally be displaced from the ratchet 10. This will permit immediate rotation of the roller 8 and this rotation will cause the cord 6 to wind around the roller 8 and thus the canvas or curtain will be quickly drawn to the lower end of the fender and retained in such position in a taut manner. The person having been struck by the fender will thus be thrown into a basket and prevented from falling beneath the wheels of the vehicle. After the operation just described the curtain is rewound on the roller 8 and the spring again placed under tension by

means of a key or the like rotating the roller as before mentioned.

The invention is positive and quick in operation, and is simple and inexpensive in construction and because of its utility and arrangement with respect to a motor vehicle, it will enhance rather than detract from the finished appearance of the vehicle.

Having described my invention, what I claim and desire to secure by Letters-Patent is:—

1. In a fender the combination of a frame secured at an angle on a vehicle, a roller secured to the upper end of the frame, a canvas wound on the roller, a cord adapted to be wound around the roller, an arm for securing the frame to the vehicle, a pawl secured on the frame and having one end engaged by a seat in the arm and a ratchet 20 in which the opposite end of the pawl normally rests.

2. In a fender the combination of forwardly reaching arms, a frame secured to and movable with respect to the arms, a spring secured to one portion of the frame and one of the arms, a seat formed in one of the arms, brace rods secured to the frame, rollers secured on one of the brace rods, a roller secured to the upper end of the frame, a ratchet arranged on one end of the roller, 25 a curtain secured to the roller, a cord secured to the roller and a pawl adapted to be retained normally by the seat in one of the arms.

In testimony whereof I have hereunto set 30 my hand in presence of two subscribing witnesses.

JACOB BARAM.

Witnesses:

EVELYN W. SPAULDING,
EDGER L. SPAULDING.
